UNITED STATES PATENT OFFICE.

JOSEPH MOSES WARD KITCHEN, OF EAST ORANGE, NEW JERSEY.

GENERATOR.

No. 874,850.

Specification of Letters Patent.

Patented Dec. 24, 1907.

Application filed March 15, 1906. Serial No. 306,223.

To all whom it may concern:

Be it known that I, JOSEPH MOSES WARD KITCHEN, a citizen of the United States of America, and a resident of East Orange, Essex county, New Jersey, have invented certain new and useful Improvements in Steam-Generators, of which the following is a specification.

My invention consists of a system of elements, the combined function of which secures economy in power production. The system is novel in the relative arrangement of the elements; and most of the elements are of novel structure.

15 The prominent elements consist of a furnace, automatic feeding grates, and other fuel burning, economizing features, a peculiar combustion chamber, a boiler and combined economizer, a combustion engine, a gas producer, a steam super-heater, a system for introducing a compressed power transmitting fluid between the combustion engine and a prime motor, a steam condenser and air heater, a system for actuating motors and 20 the motors used in the generator, means for producing induced and forced draft in correct proportions, a water purifier and evaporator, and various pumps for compressing air, steam and water, and for exhausting.

25 For convenience of consideration the generator may be described as having two fronts and two sides.

In the accompanying drawings: Figure 1 represents a vertical cross view of my invention, taken from one side and in the line of *c-c* Fig. 2, with parts left out for clearness, is partly in section, and parts are broken away. Fig. 2 represents my invention taken from one front and in the line of *b-b*, Fig. 1 30 and is a vertical cross view partly in section, with parts broken away, and with parts left out for clearness. Fig. 3 is a cross horizontal view of my generator, taken in the line of *a-a*, Fig. 1, partly in section, partly broken 35 away, and parts left out for clearness. Fig. 4 is a vertical side view of a chain grate, fuel hopper, and combustion pit wall, comprised in my invention, on a larger scale. Fig. 5 represents a single link of the chain grate 40 and is on a still larger scale, as is also Fig. 6, which represents a series of links joined by bolts. Fig. 7 is an end sectional view of a part of my invention, which is located immediately above the chain grate, and is part of 45 the wall surrounding the combustion chamber; it comprises means for introducing over

fire air for combustion, a fire arch, and a fuel shunting surface. Fig. 8 is a side view of the air introducing means shown in Fig. 7. Fig. 9 represents a metallic plate used in facing the lower front faces of my invention, and having attached thereto fuel introducing and grate shaking motors. Fig. 10 represents on a larger scale headers and tubes used in the construction of the boiler. Figs. 11, 12 and 13 represent parts of an ash pit register or ash discharger.

The reference characters represent like parts in all the drawings.

The elements of the invention are in and are grouped around and above a centrally located combustion chamber C Figs. 1, and 3. This chamber has a vertically disposed very high run. It is surrounded by a heavy brick wall, W, Figs. 1, and 3, built up from a solid foundation, and partly supported by a steel frame L, Figs. 1, and 3. This is lined with fire brick. In the lower part of the combustion chamber are located four chain grates, represented by G, Figs. 1, 2, 3 and 4, and two combustion pits represented by C⁴, Fig. 2. These pits have unusual depth and width for holding a very thick bed of fuel, most of the fixed fuel being burned in them with the aid of a forced draft of heated air 85 and some steam. A low dividing wall W⁴, Figs. 2 and 3, separates the two chain grates and one combustion pit on one front from those on the other front, thus enabling 90 separate observation of the fire surfaces and stoking management to be in manual reach from either front of the combustion chamber. Underneath the floor line are tunnels D⁴, Fig. 1, running parallel with the two fronts, enabling ashes to be drawn into ash 95 ears from the ash doors D⁵, Figs. 1 and 2.

At the top of the combustion chamber C are suspended shell boilers B, Figs. 1 and 2, from steel beams L¹, which rest on the masonry sides of the walls of the combustion chamber, and which are also connected with the general steel skeleton supporting frame L, Figs. 1, and 3. At each front of the generator and adjoining the combustion chamber is a heating cavity H, Figs. 1, 2 and 3, in which are suspended water tubes section E, Figs. 1, 2 and 3, having water tubes T, Figs. 1, 2, 3 and 10, with headers T¹, T², T³ and T⁴. These sections are all hung and arranged in their relation to other parts so that any section can be lifted from and removed from the cavity in which it hangs. The in-

terior of any header or tube can be reached and cleansed by removing a screw plug opening into the lumen of each. A group of sections is connected with the ends of each of 5 the shell boilers B, and provision for the circulation of water at the head of each section is made by passing down water through the pipe T⁵, Fig. 1, through the header T³, and upward back to the boiler through the 10 header T⁴.

The cross headers T² and T³ are only of a width equal to each group of sections, and feed water is run into each bottom cross header T² from the general feed pipe U, Fig. 15

1. Valves are placed both at the extreme top and extreme bottom of each group of headers so that if needed the generator may remain in commission even if one group of sections may need cleaning or removal for 20 repair.

There is no circulation in this boiler as generally understood other than that before noted. Cold feed water is forced in at the bottom of each group of vertical tubes, and is gradually heated in its ascent, most of 25 the steam being disengaged in the shell boilers B. Unlike most other boilers, the best efficiency of this one depends in connection with heat absorption on the lowest possible temperature of the feed water. The 30 heating cavities extend from the combustion chamber outwardly to the two fronts. These cavities are surrounded by masonry walls W¹, in which clean out doors E¹ are conveniently located, through which the interior of 35 the cavities may be cleaned with a steam spray. In certain cases I may use a mechanically actuated rising and descending scraper in these cavities. The lowest level of 40 the cavities is at a height above that of the height of a man, for the purpose of allowing the stoking attendant to walk under them and come close to the combustion chamber, the several grates, and to the passage ways provided at either side of the combustion chamber on the ground level. Access to these passage ways, which contain 45 fuel hoppers Q, is gained through the doors A¹; and from one front to the other through the doors A², which are located in a dividing 50 wall W⁷, Fig. 3. The space on both sides of the combustion chamber is divided into two air shafts Y⁴, by the wall W⁷. To the front of the shafts Y⁴ are other shafts Y³ on either side of the heating cavities.

55 Induced air for combustion is drawn into the shafts Y³ through the ventilators V², Fig. 2, up through the shafts Y³, to and through the opening I¹, Fig. 1, in the wall W⁷, thence down the shaft Y⁴ under and up through the 60 chain grates, up through the combustion chamber C, through the gas openings O, Fig. 1, down through the heating cavities H, to the lowest levels of said cavities, and thence horizontally through numerous small flues 65 into the larger smoke flue F, to the smoke

stack S, Fig. 1. The gases are thus distributed through a number of horizontally placed pipes at the bottom of the heating cavities, in order to get a uniform distribution of the heat in the cavities. Each of 70 these outlets is governed by a piston shaped or other formed valve F¹, all of which may be removed to clean the bottom of the cavities H, and also may be so disposed as to uniformly distribute the outflow of the gas 75 through them. The draft thus induced is created by the fan I, actuated by its motor Y.

The heating cavities H are surrounded by the brick walls W¹, which are supported in part by the general steel frame L. The bottom of each cavity is inclosed by non-conducting movable slabs H², Fig. 1, having metallic frames H³, Fig. 1 in the drawings. These can be hinged to allow for their easy opening for cleaning purposes. The headers T² are in a trough I², Fig. 1, filled with clay dust, which is needed to close the elongated apertures through which the connecting pipes reach the headers T² from the headers T⁴. To provide for expansion, this largeness of aperture is allowed, and the sections E swing from the top by chains depending from the beams L, and by the resting of the headers T³ on the outer masonry walls W¹. The tops of the sections at the highest level of 95 the cavities are covered in with non-conducting material, not shown, as also are the shell boilers B. Coal bins N, Fig. 1, are connected with fuel chutes J, Figs. 1 and 2, which discharge into the hoppers Q, Figs. 1 and 2, which feed on to the chain grates. The chutes J also discharge into the dust feeders J¹, Fig. 2. In the generator as here shown provision is made for burning bituminous coking coal on the grates in the lower part of the combustion 105 chamber, it being coked in being drawn into the combustion pit C⁴. The coked fuel falls into the pit C⁴, and is burned there in a thick bed, by the use of a forced draft, introduced under the grate G¹, with or without steam introduced through the pipes R¹, Figs. 2 and 4. In addition to this fuel, anthracite dust or small sized anthracite coal is fed from the top of the combustion chamber from the feeders J¹, motor actuated rolls under control determining the amount fed. The dust dropping along the walls at the sides of the combustion chamber strikes the curved shunting surfaces W³ of the fire arches K, Figs. 1, 2 and 7, and is shunted towards the combustion pit, 115 being more or less diffused in the rising gases, and is burned in the atmosphere of the combustion chamber, the larger particles of the fuel gravitating to the fuel mass below. Over fire air for combustion is forcibly introduced through the twyer apertures W², Figs. 1, 2 and 7. The air for forced draft is supplied by the fan Z, Fig. 2, actuated by its motor Y. The air thus supplied is drawn through a preliminary air heater, which is 120

125 130

- composed of tubes X^1 , Fig. 2, which pass through the water tank X ; the warm water of condensation is conveyed to the top of this tank X , and is therein cooled by the air for combustion being drawn through the tubes X^1 by the fan Z . As the water cools, it is drawn downward to replace water pumped from the bottom of the tank for boiler feeding and motor actuating purposes.
- 5 10 Water of condensation from the condenser R is injected into the top levels of the tank X through the distributing and injecting tubes X^2 , which float on the top of the water by means of the connected flexible tubes X^3 .
- 15 20 The air for combustion is further heated by being forced through the condenser R , Figs. 1 and 2, passing through vertical tubes therein placed, the air entering at the bottom and emerging from the top, being heated by exhaust steam introduced at the top of the condenser through the opening R^2 , Figs. 1 and 2. The air, after being heated by the waste steam, is further forced through the air conduits A , Figs. 1 and 2, and is carried into the 25 equalizing distributor box A^3 , Fig. 7, through the metallic brackets W^6 and contracted twyer openings W^2 , into the combustion chamber, there expanding and blowing the volatilizing gases generated on the chain 30 grates towards the zone of the greatest heat at the center of the combustion chamber. Any excess of heated air not needed for under grate or over fire combustion escapes through the overflow valves V^1 , Fig. 1, and 35 is drawn under and through the chain grates; the amount of air for combustion needed at any point is controlled by valves V , Fig. 1. Much of this heated air is carried to and discharged into the upper part of the ash pits 40 under the grates of the combustion pits. The air for induced draft is somewhat heated from the radiation from the sides of the combustion chamber in its course up and down through the shafts Y^3 and Y^4 .
- 45 50 P , Figs. 1 and 2, represents a water purifier and vaporizer. Waste steam is conveyed therethrough in the pipes P^2 , passing horizontally from one end to the other; unpurified water is passed through the purifier P at a level covering the pipes P^2 . It enters at the opposite end from the end where the waste steam enters, and its flow is regulated by valves on the inflow and outflow pipes. The outflow pipe is carried to a low level and 55 discharges into a water seal, not shown in the drawings, to prevent inflow of air being drawn into the vaporizer when a vacuum is created therein. There is space in the vaporizer above the maintained water line, and an 60 exhausting pump D^3 , Fig. 2, communicates therewith. When the water in the vaporizer is heated and the pump D^3 is working, vapor arises from the water and is forced into the air heater and condenser R at a level 65 where about the same temperature prevails as that of the vapor introduced. After descending to the bottom of the condenser, any excess of vapor along with air and water of condensation is forced by the pump D , Fig. 2, into the higher levels of the tank X , and to 70 the ash pit pipe R^1 inducing more or less of a vacuum in the condenser R . As the water which enters the vaporizer P through the pipe P^4 progresses towards the other end, it becomes more dense from the accumulation 75 of earthy salts and organic impurities, which escape ordinarily through the outflow pipe P^5 . The whole vaporizer can be internally cleaned by means of the blow-out pipe P^6 and the hand hole P^1 , Fig. 1.
- 80 85 D^1 is the conduit for air and water leading to pump D . D^2 , Fig. 1, is the water conduit leading to the pump D , Fig. 2. C^1 , Fig. 2, represents a producer gas apparatus; C^2 represents a combustion engine; M represents a 90 water pump, and M^3 represents a combined combustion engine and compressor, for compressing a medium for transmitting power from the combustion engine M^3 to a motor. This compressor is used for compressing 95 steam generated from the waste heat of the combustion engine, or for compressing and forcing steam through a super-heater, such as B^2 , Fig. 2, in the cavity Z^2 , and for forcing said compressed steam into a storage and 100 pressure equalizing inclosed tank, not shown in the drawings. Such a tank would be of ordinary cylindrical type, made of unusually strong pressure resisting sheet metal.
- 100 105 The object of the mechanical compression of steam is to allow of the production of large volumes of steam in the boiler of the generator at relatively low pressures and temperature, thus avoiding excessive strain on the boiler and decreasing risks from explosions. The pump M^3 and its connecting adjuncts leading to a motor would be of unusually strong construction, but because of the lesser weight of metal, which would be then needed in the general boilers of the generator, 110 this related arrangement would be economical. The pump M takes cold water from the bottom of the tank X , and forces it into the main leading to the feed water pipe U , and to the various motors Y , actuating the fuel 115 feeders, draft fans, shakers, and other economizing features. Pressure in the water mains is maintained and equalized by connection through the pipe M^4 , Fig. 2, with the tank M^1 , Fig. 2, the upper part of which acts 120 as a compression air chamber. This tank is supplied with a safety valve M^2 , and with a water level gage and an automatic regulator for keeping the level of the water at a proper height in its relation to the compressed air in 125 the tank. The gas producer C^1 and the engines C^2 and M^3 are connected with ordinary means, not shown in the drawings, for heating water and producing steam from the waste heat of the gas producer and from the 130

combustion engines. The steam thus produced may be run in with that produced by the generator's boilers, or it may be equalized in pressure with the steam produced by those 5 boilers, by means of the compressor M^3 . The steam super-heater B^2 , Fig. 2, is located in a cavity separate from the combustion chamber C of the boiler, but communicating therewith by the passage O^1 at a high level. Hot 10 gases are drawn through the passage O^1 and down through the cavity Z^2 by means of the inducing fan Z^1 , the control of which, through an individual motor, determines the degree 15 of super-heat imparted to the steam passing therethrough, and which is introduced in the bottom of the super-heater and taken out from the top through the pipe B^1 . The heating gases, after being drawn through the cavity Z^2 by the fan Z^1 , are blown into an adjacent economizing cavity H at a level in 20 which the usual temperature of the heating gases in the cavity H are approximately the same as those passing through the fan Z^1 .

In my invention in various parts, I introduce the principle of applying at the same 25 level heat of equal temperatures to heating surfaces, the opposite heat absorbing medium of which is of a temperature not above that of the heat applied, but at a level in 30 which the temperature is not much below that of the applied heat. Thus, in the utilization of the heat of the combustion engine, I lead the hot gases into an economizer at an appropriate level to apply this just mentioned principle, as indicated in the economizer C^3 , Fig. 2, where illustrative provision is made for applying such waste heat at 35 several levels.

The super-heater B^2 , Fig. 2, is strongly 40 made, to resist high internal pressures, and is not in a position to be damaged by the direct exposure to the excessive heat of very hot gases or flame, as is the case where a super-heater is introduced in a combustion chamber. 45

Fig. 4 represents a side vertical view of a chain grate G , a fuel hopper Q , and one lateral wall C^5 of the combustion pit C^4 , four of which grates are used in the generator. The 50 grate is supported on a sectional frame with a bed plate B^3 unitedly held rigid by the splice plate B^4 . Two bracketed uprights B^5 are bolted to B^3 , and hold the two shafts of the grate; the shaft nearest the pit C^4 has 55 sprocket wheels which run in connection with the chain web. The actuating motor Y (see Fig. 9) is connected with this shaft, and hence the chain is dragged away from the fuel hopper Q , instead of being pushed 60 from it as in other stokers. This provision allows for a looser chain web being maintained, and hence lessens friction. The sides of the fuel hopper Q are cast in one piece, with the supporting bracket under the hopper. The rear side of the hopper Q is hinged

at the top to the hopper, and the side is hinged in itself at Q^4 . The cam Q^2 pushes the side Q^3 inward, and thus regulates the flow of fuel onto the chain web. Track beams B^6 are bolted to and connect the bracketed uprights, and on these tracks run the wheels included in the chain web. Fig. 5 represents one side view of one chain web link L^2 , and the traveling wheels L^3 .

Fig. 6 represents a horizontal under side view of several of the links and traveling wheels bolted together with washers outside of the links. The top of the links L^2 are curved in harmony with the circle they travel in being carried around the actuating shaft. This enables the pointed top of the wall C^5 to be constructed close to the curvatures of the tops of the links, and to completely separate the fuel from the chain web and cause it to fall into the combustion pit. A duplicate chain grate and wall being opposite to the one described, and at a regulated distance from it, enables the fuel as it falls from both grates to more or less fill the combustion pit, the level of the fuel therein being 90 regulated by the rapidity with which the chain grates are run and the intensity of the enforced draft acting through the pit, and the activity of the grate shaking mechanism actuating the grate bars of the grate G^1 . 95

Fig. 7 represents the construction of the wall of both sides of the combustion chamber immediately above the chain grates. Heavy steel supporting beams L^4 are carried across and above the chain grates, and support the 100 masonry walls built on them. Metallic brackets W^6 are bolted to the supporting beams. Air cavities run through these brackets, connecting at one end with the air pipes A^4 , and at the other end with the twyer 105 openings W^2 . Specially formed fire brick W^6 are run between the brackets, resting on curvatures on the sides of the brackets, and form the bottom of the fire arch K . These fire brick protect the metallic brackets from 110 too great heat. Other specially formed brick are built over the brackets, forming the surface of the shunting slope W^3 of the fire arch K . The air tubes A^4 fit in the bottom of the air distributor box A^3 , and cone shaped 115 stoppers are hung into the tops of the tubes A^4 , and are drawn up or let down by chains run over the partial rim A^5 actuated by a shaft. As the stoppers are more or less lowered, the entrance of air to the air tubes is 120 shut off, and thus the air for combustion can be distributed equally into the combustion chamber C through the twyer openings W^2 .

Fig. 8 shows a rear view of the parts shown in Fig. 7. The air goes into the box A^3 125 through the air conductor A . The handle H^1 raises and lowers the cone shaped stoppers of the lifting air valves A^6 . In the same figure W^6 shows the fire brick in section, and W^6 a bracket in section. 130

Fig. 9 is a front vertical view of the metallic plates F^2 , with which are faced the lower fronts of the combustion chamber, and in which are located observation doors Y^2 , and to which are attached the motors Y , and the trip spring shaker Y^1 . This shaker consists of a horizontal bar which is moved from side to side by reciprocating cylinders on both sides. A spur S^1 on the horizontal bar 10 engages with a lever carried upward from the grate bars. As this spur S^1 is pulled one way after passing the lever a certain distance, the lever is released and is sprung back in place with a quick jerk by the spring S^2 , which 15 action dislodges the ashes from the fuel mass in the combustion pit C^4 . This jerking action is repeated with each reciprocal passage of the tripping horizontal bar. A rotary motor may be used with this shaker. Water under 20 pressure is carried to the several motors through the water conduits M^4 , each of which has an independent valve, the manipulation of which regulates the speed of the motors.

The ash discharger shown in Figs. 11, 12 25 and 13 is located below the combustion pit C^4 , and divides the ash pit there situated into an upper part and a lower part. G^2 , Fig. 11, is the bed plate of the discharger. G^3 , Fig. 12, is a sliding plate with ash moving ridges 30 G^4 . G^5 is actuated by the handle G^4 , Fig. 12. In the several parts, G^7 represents openings for the passage of ashes, and G^8 is a retaining rim. This ash discharger allows 35 ashes to be drawn from the ashes collected in the upper part of the ash pit at the bottom of the accumulated ashes, where the heat of the ashes has been conveyed upwardly, and allows particles of partly burned fuel, which pass through the grate G^1 , to complete their 40 combustion. The cool strata of ashes is sifted through the discharger into the lower part of the ash pit without carrying therewith the hot layer of ashes. G^6 are ash chutes leading from below the chain grates.

45 The connection between the pump D and the tank X and the steam introducing pipes R^1 may be of any ordinary construction that would suffice to separate the water of condensation from the air, vapor and steam. 50 For example: If the connecting pipe is run to the floor line and then returned to the pipe X^3 a water seal of sufficient depth will be formed to prevent the air, vapor and steam passing to X , while the water would gravitate there and the lighter fluids would be forced through an offset and delivered into the upper part of the ash pit to the pipe R^1 .

55 Oil from the engine collects on the surface of the water in the tank X and then is easily 60 removed.

I interpose steam or other appropriate media between the combustion engine and a prime motor in order to equalize the power produced by the explosion of gases, 65 making it more controllable and to dilute

the heat generated by the explosions, and thus secure an application of the explosive power in a motor, such as a turbine, without subjecting the motor to damaging heat.

In this generator the prominence given to 70 the force producing effect of the combustion engine in its relation with the force effected through the steam producing element proper would vary in accordance with varying attendant conditions. In large power plants 75 with conveniences for using cheap low grades of fuel in large amounts, most of the expansive force of the steam used in the prime motor would be created in the boiler proper, directly from the heat generated in the combustion chamber, and the explosive engine and its related steam compressor would be of secondary importance. In other cases, as, for example, in smaller plants using the more expensive fuel needed in making producer gas to use in the combustion engine, that engine might be the principal factor in creating power, while the means for creating steam to interpose between the intense comparatively uncontrollable power created by 80 explosion and the motor in which the steam is used, as for example in a turbine, would be of secondary importance; in some cases no outside boiler requiring a separate fire would be used. In such cases the following parts 85 and their connections would be used, viz: a producer gas generator preferably having a suction draft, a combined air heater and cooler for the newly formed gas, a gas scrubber, a water jacketed combustion cylinder, a 90 steam cylinder for sucking in steam of low pressure and forcing it to the prime motor at high pressure, an economizer boiler to receive the hot exhaust gases from the engine and generate low pressure steam therefrom, a circulatory connection between this boiler and 95 the water jacket of the cylinder, a connecting pipe from the economizing boiler to the steam exhausting and compressing cylinder, a water evaporator having the exhaust 100 steam run there-through and also connecting with the steam cylinder. With this system in operation, the steam after its expansion in the prime motor would be used over and over again without losing much of its latent heat, 105 merely needing replenishing from the evaporator.

I wish to emphasize the point that in this power generator I use the expansive force of explosive gases to compress waste steam and to force that compressed steam anywhere in the generator where its re-use is economically desirable, either to evaporate and purify feed water, to heat air, to use it under and through the fuel mass, or to force it into 120 a boiler, or to heat it by forcing it through a super heater, or to use it repeatedly in a continuous round between and through a steam motor and the gas exploding compressing means.

What I claim as new, and desire to secure by Letters Patent, is—

1. In a steam generator, the combination with a boiler, of means for producing power by gas explosion, means for utilizing said power in re-using the heat of exhaust steam, and a means for economizing the waste heat of said first named means.
2. In a steam generator, the combination with a boiler, of a first means for generating and exploding gas, a second means for heating air for combustion, a third means for producing steam from waste heat, means for separately drawing said waste through each of the second and third named means and for accurately applying said heat to said means in any desired amounts, means for the storage of a compressed medium for power transmission and for equalizing the pressure of an outflow of said medium from said storage means, means for inducing a partial vacuum in said generator, and means for compressing a medium for power transmission, all of said means co-acting with said boiler in producing steam economically, and for reducing the heat wastes in power production, substantially as shown and described.
3. In a steam generator, the combination with a boiler, of a first means for condensing waste steam and heating air, said steam being introduced at a high level and said air at a low level and being conveyed to a high level in said means, a means for exhausting air and water in said first named means, a means for purifying and evaporating water and for exhausting vapor and steam from said means and for compressing said vapor and steam, and means for conveying said vapor and steam into the first named means and under and into the fuel burned in said generator, for the purpose of economically producing power substantially as shown and described.
4. In a steam generator having a boiler, the combination of means for taking exhaust steam from a motor and for condensing said steam and for heating air with said steam, and means for taking some of said steam and passing it through a bed of burning fuel for producing a vacuum in the said first named means and for producing purified water for steam generation and for the disengagement of steam into its chemical elements preparatory to their burning in said generator, substantially as herein shown and described.
5. In a power generator, the combination of (1) means for burning fuel, (2) means for perfecting the combustion of volatilized gases comprising a vertically disposed combustion perfecting chamber having a sufficiently high run to perfect the combustion of the volatilized gases before said gases make contact with heat absorbing surfaces transmitting heat into the water contained in said generator, (3) means for converting water into steam in said generator, said means comprising provision for receiving and absorbing into said water the heat of a perfected combustion at a level above said means for perfecting combustion and for the disengagement of steam on a broad surface of water at said high level, and (4) means for heating water in divided vertically moving currents with the heat of gases traveling downwardly from a high level to a low level, said water traveling from a low level to a high level, said generator being constructed to receive cold feed water at a low temperature and to progressively heat said feed water in the travel of said water from a low level to a high level where the water is being disengaged into steam at said high level of said generator.
6. In a steam generator, the combination of (1) means for heat generation at a low level, (2) means for perfecting the combustion of volatilized gases in the vertical travel of said gases to a sufficient height from the first named means and for preventing the lateral loss of heat from said gases until after combustion has been perfected, (3) a boiler constructed in conformity to said first and second named means, said boiler comprising structural provision for the disengagement of steam over a broad surface of water in said boiler at a high level in said generator and to receive the first application of heat generated in said generator for the absorption of the most intense heat, and (4) an economizer part conforming in structure with and paralleling said other named parts and being arranged to progressively heat water and to discharge steam into said named boiler and to pass the heating gases produced in said generator progressively from above downward, and for an exit of said gases at a low level of said economizer part, said economizer part, being constructed to heat water in divided vertically traveling currents and for the progressive heating of said water in a travel from a low level to a high level.
7. In a steam generator, the combination with a boiler constructed and disposed to receive the highest heat generated in said generator, an adjunct boiler and economizer to receive the heat of the heating gases after the gases have passed over the heating surfaces of the said boiler, said adjunct boiler and economizer comprising means for securing a flow of gases from a high level to a low level therein, and means for heating air and furnishing pure feed water from exhaust steam, said last named means being constructed to introduce steam at a high level in said means and to pass air through said last named means from a low level to a high level.
8. In a steam generator, the combination with a boiler, of a first means for purifying water by evaporating water into vapor or steam for replenishing the steam leakages of said generator, said first means having provision for passing horizontally through said

- means water from one end to the other and for controlling the amount of water thus passed through said means, said means having conduits for passing steam through said 5 means in a reversed current to that traveled by said water and for heating said water progressively in its passage through said means, said named means having a vapor and steam space therein, a second means for inducing a 10 vacuum in said first named means and for drawing vapor and steam therefrom and passing the same to a means for condensing steam and heating air and for forcing the same to and through the fuel mass of said 15 generator, a third means for condensing steam and heating air, steam being introduced at the top of said third named means and air being passed therethrough from below upwards and out of the top of said third 20 named means, a fourth means for receiving and storing water of condensation, the hot condensed water being received at the top of said fourth named means and having outlets for cooled water at the bottom of said fourth 25 named means, a fifth means for passing air through the water of said fourth named means from a low level to a high level for primarily heating said air and for cooling said water of condensation, a sixth means for conveying the air from the fifth named means to and through the third named means, and a 30 seventh means for exhausting air, vapor and water from said third named means and for passing the same into the top levels of water 35 stored in the fourth named means, all for the economical production of steam substantially as shown and described.
9. In a steam generator, the combination of first a boiler, second a motor actuated element, third a motor, fourth a means for storing water, fifth a means for storing water and air under pressure, sixth a means for drawing water from the first named means and forcing it into the fifth named means, 40 and a seventh means for conveying water under pressure from the fifth named means to a motor and for conveying water from a motor to the fourth named means, substantially as herein shown and described and 45 for the purpose set forth.
10. In a steam generator, the combination with a boiler, of a means for the surface condensing of steam and for heating air, said means being arranged to pass air for heating 50 into one end of and through said means, and means for removing air and water of condensation from the first named means, substantially as herein shown and described and for the purposes set forth.
11. In combination with a steam generating apparatus, an economizer, said economizer being provided with means to receive 55 warm water of condensation at a high level and for conveying through said economizer a flowing heat absorbing medium from a low 60 level to a high level.
12. In combination with a steam generator having a boiler and a storage reservoir for steam, means for additionally compressing the steam primarily produced in said 65 boiler and for superheating said compressed steam and for conveying to and storing in said reservoir, said compressed steam, and means for conveying said steam to a motor, said combination co-acting for equalizing 70 the expansive force of the steam, substantially as herein shown and described.
13. In a steam generator having a boiler for steam production, the combination of means for heating a flowing heat absorbing 75 fluid passing from a low level to a high level by the heat of exhaust steam, vapor and water of condensation, the heat of said steam, vapor and water being first applied in said means at a high level and being progressively applied downward in said means 80 to a low level, said means being in two parts, in one (first) part of said means the steam and vapor heating the said absorbing fluid and in the other (second) part of said means 85 the water of condensation heating the said fluid, the said fluid being first heated at a low level and further heated in its progress from below upward through the second named part and then being further heated in 90 its progress upward through the first named part, and means for mechanically producing the flow of said fluid through the two named parts, said elements co-acting to economically produce steam.
14. In a steam generator producing steam for use in a motor, and in combination with said generator, means for compressing and forcing a medium carrying the waste heat of the motor into any cavity or any part of said 95 generator at any level where the waste heat may be used regeneratively in the production of steam, substantially as shown and described, and for the purposes set forth.
15. In a steam generator, the combination of (1) a vertically elongated combustion space having a source of heat at the bottom thereof, (2) means for preventing the lateral loss of heat from said space, except at a high 100 level thereof, (3) a boiler, said boiler comprising heat absorbing surfaces at the top of said combustion space for the absorption of the first intensity of heat conveyed through said space upwardly, and broad water surfaces for the disengagement of steam, said boiler comprising furthermore, economizer parts located laterally and in the line of the vertical length of said combustion space and comprising vertically arranged heating tubes arranged in sections, said sections having horizontally disposed headers at the bottom thereof and headers at the top 105 thereof disposed at an upwardly projected

angle at the top of said sections to, and connected with and communicating with the part of the boiler located above the combustion space, said boiler being constructed to receive feed water at the lowest level thereof and for the emission of steam at the highest level thereof, (4) heating cavities adjacent to said combustion space, into which cavities the section parts of said boiler are suspended, said cavities having apertures at the top for the entrance therein of heating gases, and outlets at the bottom for the exit of waste products of combustible gases, (5) means for inducing a draft through said generator, and (6) means for forcing a draft in said generator, said named parts of said generator being constructed and arranged to allow for the introduction of fuel from the two opposite sides of said generator, and for the progressive flow of feed water through said boiler from a low level to a high level thereof, and for progressive contact of heating gases with said boiler from the highest levels of the heating surfaces of said boiler to the lowest levels of said surfaces.

16. In a steam generator, the combination of a boiler, a high run combustion chamber, a gravity fuel feeding mechanism, an air feeding and air diffusing mechanism, an economizer for condensing steam and heating air, a water purifier and evaporator, said evaporator passing waste steam through the water in said purifier for the vaporization of said water, means for producing explosive gas, a combustion engine, a system for distributing the power generated in said engine to the motors of said generator, said motors, means for conveying steam from said generator to a motor and for returning waste steam from said motor into the steam storage means of said generator, means for compressing steam or other power transmitting media, a steam superheater, and means for introducing waste heat at various levels in said generator, all substantially as shown and described.

17. In a steam generator, the combination of means for storing compressed steam, a superheater, a steam condenser and air heater, means for mechanically inducing a draft, means for forcing a draft, means for automatically feeding fuel, means for supplying steam and applying air in said generator in a practically controlled manner, a combustion engine for creating power, means for storing the power created by said engine and distributing the power to motors actuating the draft, pumps and fuel feeding provisions of said generator and said motors, all connected and co-acting substantially as shown and described.

18. In a steam generator, the combination of a boiler, a motor, means for reduction of the temperature of a power transmitting medium after said medium has acquired

propulsive force, and means for delivering said medium to said motor, the aforesaid means comprising provision for storing said medium in a compressed state.

19. In a steam generator, the combination of a boiler, means for mechanically inducing a draft through said generator, means for forcing a draft in said generator, and means for forcing water and air bearing the lower degrees of heat developed in said generator that remain unabsorbed after the more intense degrees of heat have been absorbed in said boiler, said last named means providing for the travel of water and air upwardly in vertically moving currents and for the travel of heat bearing fluid media in vertically descending currents, said two means for producing draft in said generator co-acting with the other elements in said combination to heat water, air or other fluids with either exhaust steam or with heated gases.

20. In a steam generator, the combination of (1) a steam boiler, (2) means for generating heat and supplying heat to said boiler, (3) a draft inducer for producing a draft through the passages of said boiler, (4) an internal combustion engine for supplying power to run said draft inducer, (5) means for compressing a fluid with the force of explosion generated in said engine, (6) means for storing said fluid and giving expansive pressure to said fluid and for conveying said fluid and for utilizing the expansive force of said fluid in actuating said draft inducer.

21. In a steam generator, the combination with a boiler, of (1st) a gas explosion engine for supplying power for actuating the motoring devices of said boiler, (2nd) said devices, (3rd) means for utilizing the heat generated in said engine from explosion in the heating of water and producing steam, said heat being passed through said third named means from a high level to a low level, and said water and steam being passed through said third named means from a low level to a high level, and (4th) means for conveying water bearing heat from the first named means into the third named means at a level where the temperature is substantially the same as that of the water which is thus conveyed; said combination acting adjunctly with said boiler in producing steam economically.

22. In a steam generator, the combination of (1st) a boiler, (2nd) a vertically elongated combustion chamber, (3rd) a heat economizing cavity adjacent to said combustion chamber, (4th) means for accurately controlling the superheat of the steam generated in said generator and for preventing damage to the structure of said last named means, and (5th) means for economizing relatively low degrees of heat passing from the fourth named means; said 4th and 5th named means being exemplified by a superheating

cavity separate from said 2nd and 3rd named elements, vertically arranged steam pipes for conveying steam through said superheating cavity from a low level to a high level, a gas conduit leading from a high level of said combustion chamber to a high level of said superheating cavity, a fan for drawing hot gases through said superheating cavity from a high level to a low level and for forcing said 10 gases into said heat economizing cavity at a level where the temperature is substantially the same as that of the gases therein found, and a controlling motor connected with said fan for varying the rate of travel of gases 15 through said superheating cavity.

23. In a steam generator, the combination of a boiler, mechanical means for inducing at will any desired rate of travel of heating gases through the heat transmitting passages 20 of said boiler, said means comprising provision for producing and exploding gas and for economizing the latent heat of exhaust steam regeneratively in the production of steam, and means for economizing the waste 25 heat of said provision for exploding gases in the adjunct production of steam in said generator.

24. In a steam generator, the combination of (1) a combustion chamber provided with 30 an elongated vertically disposed run for burning gases and a surrounding heat non-conducting wall, (2) means for gaining access to said combustion chamber from two fronts and two sides, (3) heating cavities between 35 said combustion chamber and the two fronts of said generator, said cavities extending vertically upward from a level of about seven feet above the base of said generator, (4) means for securing the removal of dust and 40 soot from said cavities, and (5) a boiler, said elements being constructed, arranged and coactively disposed to first apply heat to said boiler at the top of said chamber and for ap-

plying decreasing amounts of heat to said boiler progressively in a downward travel of 45 heating gases through said cavities and for the heating of water in the upward travel of water through said cavities.

25. In a steam generator, the combination of (1) a high run combustion chamber conveying heating gases from a low level to a high level therein, (2) adjacent cavities, (3) hot gas passages extending from the top of said combustion chamber to the top of said heating cavities, (4) gas exits at the bottom 55 of said cavities, (5) a steam boiler conforming to the top of said combustion chamber and to said cavities, and (6) a metal frame work for holding together and supporting the various parts of said generator, said frame work 60 being so constructed in relation to the other parts of said generator as to allow the removal of sections of said boiler from said cavities through the inter-spaces of said frame work.

26. In a power generating system, the combination of (1) a boiler, (2) a furnace for supplying heat to said boiler, (3) means for inducing a draft through the heating passages of said boiler, (4) an explosion engine 70 for furnishing individually and apart from the steam power generated in said system motive force for actuating the motors of said generating system, (5) means for utilizing the spent gases from said explosion engine, 75 for heating water and producing steam, and (6) a hydraulic mechanism for transmitting the power generated by said engine to said motors.

Signed at New York, N. Y. this 12' day of 80 March 1906.
